UNITED STATES PATENT OFFICE.

JAMES FISHWICK, OF MAINVILLE, OHIO.

HAND CRIMPING-TOOL.

SPECIFICATION forming part of Letters Patent No. 271,052, dated January 23, 1883.

Application filed June 10, 1882. (No model.)

To all whom it may concern:

Be it known that I, JAMES FISHWICK, of Mainville, in the county of Warren and State of Ohio, have invented a new and Improved 5 Hand Crimping-Tool; and I do hereby declare that the following is a full, clear, and exact description of the same, reference being had to the accompanying drawings, forming part of this specification, in which—

10 Figure 1 is a view in perspective of the crimping-tool opened. Fig. 2 is a plan view, showing in dotted lines the oblique adjustment of the corrugated plates, and Fig. 3 is a section through the line *x x*.

15 My invention relates to an improved construction of hand crimping-tool to be supported and operated by one hand for crimping the hair, or for crimping ruffles and fancy articles of wearing-apparel.

20 It consists in a handle made of a pair of levers pivoted together, like a pair of scissors, and bearing at their ends opposite the handles corrugated crimping-faces, of brass or other non-corrosive metal.

25 It also consists in the means for connecting said levers to the crimping-faces by pivoting them to a flat plate and riveting said plate to the crimping-faces, whereby the crimping-face is stiffened, and the angle of the handles to the crimping-faces may be varied to suit the convenience of the user.

In the drawings, *A A* represent the two levers of my crimping-tool, pivoted together at *a*, having handles *b b*, for use after the manner of a 35 pair of scissors or shears.

To the outer ends of the levers are attached the two crimping-faces *B B*, made of corrugated sheet-brass or other non-corrosive metal, the ridges of one face being arranged to fit into the 40 grooves of the other.

For connecting the levers to the crimping-faces, plates *C C* are riveted to the latter transversely to the corrugations, and to this plate the levers are pivoted at *c*, with a stiff or frictional joint, so as to preserve a constant position with respect to the crimping-faces while in use, but be capable of an angular adjustment about said pivot, as shown by dotted lines, so as to allow the handles to be put in different positions with respect to the crimping-faces, as convenience may require. The plates *C* permit this adjustable connection, and also serve to stiffen the crimping-faces transversely to their corrugations. 45

For using the crimping-tool the corrugated faces are heated in any desired manner, and then brought together on the article to be crimped. 50

I am aware of the fact that a hand crimping-tool has been constructed with the crimping-faces between the pivot and the handles, and I therefore only claim the relative arrangement of these parts shown and described. 60

Having thus described my invention, what I claim as new is—

1. A crimping-tool consisting of a pair of levers pivoted together in the middle, and having upon one side of said pivot a pair of handles and upon the other side a pair of corrugated crimping-faces, adapted to be operated 70 like a pair of scissors, as described.

2. A crimping-tool consisting of the pivoted levers *A A*, the plates *C C*, pivoted to the ends of said levers, and the corrugated crimping-faces *B B*, riveted to the plates *C*, substantially 75 as shown and described.

JAMES FISHWICK.
